handle portion secured to the rear end of said bar, a sheath closely embracing said bar and slid-
able thereon, a coil spring around said bar and positioned between said handle portion and said sheath, a second toothed jaw hinged to said first jaw at its rear upper portion and to said sheath at its lower rear portion, and a projection on the rear end portion of said sheath to facilitate its manual movement against the action of said spring and toward said handle portion.

2. In a device of the class described, an elongated bar rectangular in cross-section, a toothed jaw formed on the forward end of said bar, a handle portion secured to the rear end of said bar, a sheath closely embracing said bar and slid-
able thereon, a coil spring around said bar and positioned between said handle portion and said sheath, a second toothed jaw hinged to said first jaw at its rear upper portion and to said sheath at its lower rear portion, a projection on the rear end portion of said sheath for facilitating its manual movement against the action of said spring and toward said handle portion, and a flexible member embracing said spring.

3. In a device of the class described, an elongated bar, a toothed jaw formed on the forward end of said bar, a handle portion secured to the rear end of said bar, a sheath closely embracing said bar and slid-
able thereon, a coil spring around said bar and positioned between said handle portion and said sheath, a second toothed jaw hinged to said first jaw at its rear upper portion and to said sheath at its lower rear portion, a projection on the rear end portion of said sheath for facilitating its manual movement against the action of said spring and toward said handle portion, and a flexible member embracing said spring.

4. In a device of the class described, an elongated bar, a toothed jaw formed on the forward end of said bar, a handle portion secured to the rear end of said bar, a sheath closely embracing said bar and slid-
able thereon, a coil spring around said bar and positioned between said handle portion and said sheath, a second toothed jaw hinged to said first jaw at its rear upper portion and to said sheath at its lower rear portion, a projection on the rear end portion of said sheath to facilitate its manual movement against the action of said spring and toward said handle portion.

5. In a device of the class described, an elongated bar, a toothed jaw formed on the forward end of said bar, a handle portion secured to the rear end of said bar, a sheath closely embracing said bar and slid-
able thereon, a coil spring around said bar and positioned between said handle portion and said sheath, a second toothed jaw hinged to said first jaw at its rear upper portion and to said sheath at its lower rear portion, and a projection on the rear end portion of said sheath to facilitate its manual movement against the action of said spring and toward said handle portion.

JAMES E. BARTRUG.
